UNITED STATES PATENT OFFICE.

ALBERT F. STAPLES, OF BROOKTON, MASSACHUSETTS.

CASH-RECORDER.

No. 856,874.

Specification of Letters Patent.

Patented June 11, 1907.

Application filed March 19, 1906. Serial No. 306,700.

To all whom it may concern:

Be it known that I, ALBERT F. STAPLES, residing at Brockton, in the county of Plymouth and State of Massachusetts, have invented a certain new and useful Improvement in Cash-Recorders, of which the following is a full, clear, and exact description, reference being had to the accompanying drawings.

10 My invention relates to cash recorders wherewith there is employed a recording tablet or similar device on which the salesman or other operator makes an entry prior to opening the cash drawer, whether such entry be 15 for the purpose of recording a sale, money received on account, or cash paid out.

One object of the invention is to provide means making it necessary for such entry to be made before the opening of the cash receptacle.

A further object of the invention is to provide such receptacle with a novel style of combination mechanism whereby the opening of the receptacle is normally prevented 25 unless the proper combination be first operated.

A further object of the invention is to provide devices of this character with an alarm signal which will be sounded when there is 30 any improper manipulation of the devices for opening the cash receptacle, and particularly when there is improper manipulation of the combination mechanism.

A still further object of the invention is to 35 provide means whereby the mechanism for opening the receptacle may be locked against operation as well as to provide means whereby the combination mechanism may be locked or set so as to render it ineffective to prevent 40 opening of the receptacle, as when a cashier operates the same.

The invention consists in the improved cash recorder hereinafter described, as defined in the claims.

45 Referring to the drawings, Figure 1 represents a perspective view of a cash recorder constructed in accordance with my invention. Fig. 2 represents a top plan view of such recorder with the top removed. Fig. 3 represents a longitudinal section of the recorder taken on the correspondingly-numbered line of Fig. 2, showing the cover, pad, and supporting frame. Fig. 4 represents a trans-

50 verse section taken on the correspondingly-numbered line of Fig. 2. Fig. 5 represents a detail in elevation of a portion of the combi-

nation mechanism. Fig. 6 represents a detail of the combination sides, and of one of the locks therefor, the dotted lines representing the positions of the parts when locked. Fig. 7 represents a detail of the cash drawer and Fig. 8 represents a detail of the alarm bell and the adjacent portion of the drawer, showing the manner in which the opening of the drawer sounds the alarm bell.

The cash receptacle consists of a sliding drawer 1 having a suitable number of compartments 2 for the reception of the money, and mounted within a box or casing 3 having a horizontal partition 4 interposed between the top and bottom thereof. Between the partition and the cover 5 there is formed a compartment 6 where are located the combination mechanism, the alarm signal employed therewith, the devices for holding such mechanism "off" or in locked position, and also portions of the drawer locking and releasing mechanism and of the alarm bell which is operated when the drawer is opened.

The cover comprises a hinged lid 7 which is provided with a manual recording device, the pad 8 supported on a frame 9, said frame carrying a member which is adapted to engage and operate the mechanism for unlocking the drawer. The details of construction of this member, and of the means whereby the movement of the frame 9 may unlock the drawer will be described hereinafter. As is customary with devices of this kind, the drawer 1 is engaged at the rear end thereof by a spring 10 tending to open the same. This spring is located between the rear end of the drawer and the adjacent rear wall of the casing 3 and is of such length as to be placed under considerable compression when the drawer is closed.

The drawer is prevented from being opened by the spring by means of a latch 11 projecting through an opening 12 in the partition 4 and through an opening 13 in a plate 14 carried by the rear end of the drawer. With the parts as above described, the spring will be kept under compression but will be ineffective to open the drawer by reason of the latch 11 engaging the plate 14. In order to make the opening of the drawer dependent upon the entry of a record by the appropriate salesman or operator, I have devised the following unlocking mechanism.

Drawer unlocking mechanism.—The drawer unlocking mechanism comprises broadly means for releasing the latch 11 from en-

gagement with the plate 14, but the operation of this means is dependent upon the depression of the support 9 which carries the pad, and the operation of this support 5 is itself dependent upon the prior manipulation or adjustment of the combination mechanism.

The latch is connected with and forms part of an arm 15 which extends above the 10 partition 4 and is carried by a hub or sleeve 16 provided at one end with a trunnion 17 extending through a bracket 17^a. This hub or sleeve is recessed at the end opposite the trunnion 17 for the reception of a stud 18 on 15 an operating arm 19, set screws 20 being employed to adjustably connect said stud and arm to said sleeve 16. The arm 19 is provided with a trunnion 21 which is pivoted in a bracket 22 carried by the partition 4. A 20 spring 23 is placed around a portion of the stud 18 with one end in engagement with the partition 4 and the other end in engagement with the arm 19, to hold the same in proper 25 relation to its supporting means and to afford sufficient resistance to the depression of said arm. The base of the bracket 17^a is provided with one or more guide lugs 17^b for the arm 15. The means for operating the arm 19, and with it the latch 11, consists 30 of a horizontal strip 24 carried by a vertical member 25 depending from the supporting plate 9, the lid 7 being slotted to permit the passage of such member. The plate 9 is provided with one or more pins 26 projecting 35 through the lid 7, springs 27 being interposed between the plate and the lid to hold the plate 9 normally in raised position.

Combination mechanism.—With the arrangement of parts as above described, 40 when the salesman or other operator makes a record on the pad 8, the weight of his hand will depress the pad and its support and bring the strip 24 into engagement with the projection 28, thereby operating the 45 arm 19 to release the drawer latch and permit the spring 10 to open the drawer. To prevent unauthorized persons from obtaining access to the cash drawer, I interpose combination mechanism between the record 50 receiving device and the latch operating lever, whereby it will be necessary to set or adjust such mechanism in a particular combination before such operation can take place. This mechanism consists of a plurality of bars or slides 29 arranged transversely of the casing and supported on the 55 partition 4, being spaced by and guided between plates 29^a secured to the partition 4. These slides are of sufficient length to project beyond the plate 24 and their upper surfaces are so located as to normally prevent the strip 24 from engaging the projection 28 and thereby operating the drawer latch. Each of these slides is connected, at the end 60 65 remote from the plate 24 with a link 29^b

which is itself connected with a bell crank lever 30, the bell crank levers of all the slides being pivoted on a rod 31 at the side of the casing. The other branch of each lever projects through the side of the casing and terminates in a downwardly directed concaved enlargement 32 adapted to be conveniently engaged by a finger of the operator. The operating ends of these levers are arranged in line and may be protected by 75 means of a suitable hood attached to the side wall of the casing.

At a suitable distance from its inner end, each slide 29 is provided with a slot 33 of a sufficient width to permit the passage of the strip 24 and of sufficient depth to permit said plate to depress the arm 19 enough to disengage the latch 11 from the plate 14. An adjustable connection is provided between each 80 slide and its link 29^b. This adjustable connection is made by overlapping the ends of the slide and link, making a lap joint, and providing one end with a slot and the other with a threaded hole registering with said slot. The end of the link may have the slot 85 and the end of the slide the threaded hole. A channel-shaped clip 34 is applied to the overlapping ends to hold them in alinement. By means of a screw 35 extending through a hole in the clip, through the slot and into the 90 threaded hole in the slide end, the parts are firmly held together and any one or more of the slides may be adjusted in effective length so as to bring its slot 33 out of alinement with the slots in the remaining slides and out of the 95 path of movement of the strip 24. For instance, the second and third slides may be adjusted in the manner shown in Fig. 6, to bring their slots out of alinement with the slots in the remaining slides. By pressing the ends 100 of the bell crank levers connected to these slides, the slides may be operated to bring their slots into alinement with the slots in the other slides, and the operator may then depress the pad or other recording device and 105 with it the support 9 and strip 24 until the latter engages the projection 28 on lever 19, thereby withdrawing the latch 11 and permitting the drawer to open.

Alarm signal.—To give warning in case an 110 unauthorized person attempts to open the drawer, I make use of an alarm device which is preferably an electric bell 36, the push button 37 of which is operated when the wrong combination is manipulated. Adjacent the 115 ends of the slides, I provide an operating device for the button. This operating device consists of a flexible metal bracket 38 having its base fastened to the partition 4 adjacent the ends of the slides. From this base there 120 projects an upwardly extending portion of the bracket in such position as to be engaged by any one of the slides whose slot is in the 125 path of movement of the plate 24. From this upwardly extending portion projects a 130

horizontal extension 39, the end of which is in close proximity to the push button 37. The pressing of the lever of a slide whose slot is in the path of movement of the strip 24, will cause the end of such slide to engage the bracket 38 and thereby ring the bell 36.

As is usual with cash drawers of this type, means are provided whereby the drawer on opening will sound an alarm by ringing a bell.

- 5 40 designates a bell having a striker 41, said striker being carried by an arm 42 pivoted to a stud 43 and provided with an arm 44. Pivotated to the end of the arm 44 is a bypass 45, movable with reference to the arm 44 in the direction of the arrow, but being connected to operate said arm 44 when moved in the opposite direction from the position shown in Fig. 8. A spring 46 holds the upper end of the bypass 45 in the path of movement of the 10 plate or projection 47 carried by the rear end of the drawer. When the drawer is pushed inwardly, the plate or projection 47 merely depresses the end of the bypass 45 in the direction indicated by the arrow without operating the striker. When the drawer is released, however, the projection 47 engages the face 48 of the bypass and rocks the arm 44 to the right. When the projection 47 clears the arm 45, the spring 49 brings the striker into 15 engagement with the bell.

The cash recorder may be operated by a cashier, in which case it will ordinarily be unnecessary to use the combination mechanism, that is to say, the slides may be set so that the 20 slots are all in alignment and are in the path of movement of the plate 24. All that is necessary on the part of the cashier is to make an entry on the recording device or pad 8 and the weight of the hand in making such 25 entry will be sufficient to depress the pad and its support and open the cash drawer. If, however, the cashier should be called away, it will be desirable to operate the drawer with the combination "on." A convenient manner 30 of enabling the cashier to operate the drawer without the necessity of manipulating the combination is to operate the levers of the slides so set to bring their slots in alignment and then temporarily secure them in this 35 position. Each slide is provided in its inner portion with a slot 50 on the under side thereof. These slots are so located as to be in alignment when the slots 33 are in alignment.

50 51 designates a lock, by turning which in one direction a flexible lock plate 52 is brought up into the slots 50. When in this position, the lock plate will hold the slides with all of the slots 33 in alignment, and the drawer can be opened by the cashier without 55 the necessity of manipulating any of the levers 31. When called away, however, the cashier turns the key in the opposite direction, which allows the lock plate 52 to drop, and the slide or slides which have been previously 60 set in locking position will then have their

slots 33 out of alignment with the slots in the remaining slides. An attempt to operate the combination mechanism when thus locked "off" will still result in ringing the alarm, for the lock plate is made of flexible 70 material, which will permit it to yield under the pressure applied to the ends 32 of the bell crank levers.

For further safety, I provide means whereby the unlocking of the drawer, even by a 75 person acquainted with the combination, may be prevented, while an unsuccessful attempt to do so will result in sounding an alarm. The links 29^b connected with the outer portions of the slides are each provided 80 with a slot 53 in the under portion thereof. These slots are in alignment and, as the relative positions of these links are not changed except as the levers 30 are manipulated, the slots will always be normally in alignment. 85 54 designates a lock provided with a key, by turning which in one direction a lock plate 55, similar to lock plate 52, will be brought up into the slots 53 thereby preventing the relative movement of the slides necessary to 90 unlock the drawer. This plate, like the plate 52, is flexible and will permit a sufficient movement of any of the slides whose inner end may be in proximity to the plate 55 to engage the same and sound the alarm. When 95 it is desired to operate the combination in the ordinary manner, the key in the lock 54 will be turned in the opposite direction which will allow the lock plate 55 to drop out of engagement with the slots 53. As a further 100 check, I provide for the drawer a counter 56, which may be carried beneath the lid 7, said lid being provided with a suitable sight opening 57 for the inspection of the counter. This counter is provided with an operating 105 arm 58 which is connected to the strap 24 by means of a suitable arm 59 whereby, on depressing the pad and its support a sufficient distance to release the drawer, the counter is operated. In this manner, the 110 proprietor can ascertain how many times the drawer has been opened in the course of a day and can compare this number with the number of entries on the pad, thereby enabling him to ascertain whether or not the 115 drawer has been opened without making an entry.

The invention is not limited to the details of construction and operation of the illustrated embodiment of the invention, but 120 may be embodied in other forms broadly defined in the claims.

Having now described the invention, what is claimed is:—

1. A cash recorder, having, in combination, a cash receptacle, locking means for normally retaining the receptacle in closed condition, a vertically movable support for a record sheet, and connections between the locking means and the support acting to re- 125 130

lease the cash receptacle when the support is given a single movement from its normal position, substantially as described.

2. A cash recorder, having, in combination, a cash receptacle, locking means for normally retaining the receptacle in closed condition, a vertically movable support for a record sheet arranged in convenient position for writing thereon, and connections between the support and the retaining means acting to release the cash receptacle when the support is depressed from its normal position, substantially as described.

3. A cash recorder, having, in combination, a cash drawer, a latch normally retaining the drawer in closed position, a vertically movable support for a record sheet, and connections between the support and the latch operating to release the drawer when the support is given a single movement from its normal position by the hand of the operator, substantially as described.

4. A cash recorder, having, in combination, a cash drawer, a latch normally retaining the drawer in closed position, a vertically movable support for a record sheet, and connections between the support and the latch operating to release the drawer when the support is depressed from its normal position, substantially as described.

5. A cash recorder, having, in combination, a cash receptacle, a movable support for a record sheet, combination-lock mechanism, a single means for normally retaining the cash receptacle in closed condition connected with the movable support and the combination-lock mechanism so as to be unlocked only by the movement of the movable support and operation of the combination-lock mechanism, substantially as described.

6. A cash recorder, having, in combination, a cash receptacle, a vertically movable support for a record sheet, combination-lock mechanism, means for normally retaining the cash receptacle in closed condition connected with the support and the combination-lock mechanism so as to be unlocked only by the single movement of the support from its normal position and operation of the combination-lock mechanism, substantially as described.

7. A cash recorder, having, in combination, a cash receptacle, a movable support for a record sheet, combination-lock mechanism, means for normally retaining the cash receptacle in closed condition connected with the support and the combination-lock mechanism so as to be unlocked only by the single depression of the support from its normal position and operation of the combination-lock mechanism, substantially as described.

8. A cash recorder, having, in combination, a cash receptacle, means for retaining the cash receptacle in closed condition, a

movable support for a record sheet, connections between the retaining means and the support for releasing the cash receptacle when the support is moved, and independently operable combination-lock mechanism 70 to prevent releasing movement of the support, substantially as described.

9. A cash recorder, having, in combination, a cash receptacle, means for retaining the cash receptacle in closed condition, a vertically movable support for a record sheet, connections between the retaining means and the support for releasing the cash receptacle when the support is moved, and independently operable combination-lock mechanism 75 to prevent releasing movement of the support, substantially as described.

10. A cash recorder, having, in combination, a cash receptacle, means for retaining the cash receptacle in closed condition, a vertically movable support for a record sheet, connections between the retaining means and the support for releasing the cash receptacle when the support is depressed, and independently operable combination-lock mechanism 80 to prevent releasing movement of the support, substantially as described.

11. A cash recorder, having, in combination, a recording device, a normally locked cash receptacle and mechanism co-operating 95 with the recording device for unlocking the cash receptacle, comprising combination-lock mechanism, and means for holding the combination-lock mechanism "off," substantially as described.

12. A cash recorder, having, in combination, a recording device, a normally locked cash receptacle and mechanism co-operating with the recording device for unlocking the cash receptacle comprising combination-lock 105 mechanism and means for locking the combination-lock mechanism in locked position, substantially as described.

13. A cash recorder, having, in combination, a recording device, a cash receptacle, 110 combination-lock mechanism (co-operating with the recording device in the unlocking operation) for locking the receptacle, and an alarm device connected with the combination-lock mechanism operating to give an 115 alarm upon an unsuccessful attempt to operate the combination-lock mechanism, substantially as described.

14. A cash recorder, having, in combination, a recording device, a cash receptacle, 120 combination-lock mechanism (co-operating with the recording device in the unlocking operation) for locking the cash receptacle comprising a plurality of tumblers, an alarm device and connections between the combination-lock mechanism and the alarm device operating to give an alarm upon a movement of wrong tumblers, substantially as described.

15. A cash recorder, having, in combination,

- tion, a recording device, a cash receptacle, combination-lock mechanism (co-operating with the recording device in the unlocking operation) for locking the cash receptacle, 5 means for holding the combination-lock mechanism "off," and an alarm device operated by an attempt to operate the combination-lock mechanism, substantially as described.
- 10 16. A cash recorder, having, in combination, a recording device, a cash receptacle, combination-lock mechanism (co-operating with the recording device in the unlocking operation) for locking the cash receptacle, 15 means for locking the combination-lock mechanism in locked position, and an alarm device and connections between the combination-lock mechanism and the alarm device operating to give the alarm upon an attempt 20 to operate the combination-lock mechanism, substantially as described.
17. A cash recorder, having, in combina-
- tion, a cash receptacle, a pad holder, a device for retaining the cash drawer closed, and connections between the pad holder and the retaining device operating to release the drawer upon a depression of the pad holder from its normal position, substantially as described. 25
18. A cash recorder, having, in combination, a cash drawer, a pad holder, a device for retaining the cash drawer closed, combination-lock mechanism, and connections between the pad holder, the combination-lock mechanism and the drawer retaining device operating to release the drawer upon a simultaneous operation of the combination-lock mechanism and a depression of the pad holder, substantially as described. 30 35

In testimony whereof, I hereunto affix my signature in the presence of two witnesses.
